US00D343170S

United States Patent [19]

Gilpin et al.

[11] Patent Number: Des. 343,170

[45] Date of Patent: ** Jan. 11, 1994

[54] HANDHELD LASER DIODE SCANNER

D. 317,154 5/1991 Allgeier D14/116
D. 320,013 9/1991 Siemiatkowski et al. D14/116
4,652,750 3/1987 Eastman et al. 250/239

[75] Inventors: David W. Gilpin, Everett; Darryl L. Carver, Seattle, both of Wash.

Primary Examiner—Wallace R. Burke

Assistant Examiner—Freda S. Nunn

Attorney, Agent, or Firm—Seed and Berry

[73] Assignee: Intermec Corporation, Everett, Wash.

[57] CLAIM

The ornamental design for a handheld laser diode scanner, as shown and described.

DESCRIPTION

FIG. 1 is a top, front and left-side perspective view of a handheld laser diode scanner showing our new design; FIG. 2 is a bottom, rear and right-side perspective view of the handheld laser diode scanner of FIG. 1 shown with a boot over its scanner head;

FIG. 3 is a bottom, rear and right-side perspective view of the handheld laser diode scanner of FIG. 1; and, FIG. 4 is a top, front and left-side perspective view of the handheld laser diode scanner of FIG. 1 shown with the boot illustrated in FIG. 2.
